UNITED STATES PATENT OFFICE.

HARLIN EDGAR STEWART, OF CEREDO, WEST VIRGINIA.

SUSPENDING DEVICE.

1,111,812.

Specification of Letters Patent. Patented Sept. 29, 1914.

Application filed November 17, 1913. Serial No. 801,484.

To all whom it may concern:

Be it known that I, HARLIN EDGAR STEWART, a citizen of the United States, residing at Ceredo, in the county of Wayne and State 5 of West Virginia, have invented certain new and useful Improvements in Suspending Devices, of which the following is a specification, reference being had to the accompanying drawings.

10 This invention comprehends certain new and useful improvements in suspending devices and has for its primary object to provide a device of extremely simple construction and which may be employed for suspending hammocks and the like and which will be strong and durable as well as highly efficient in use.

Another object is to provide a device of this character which will include an oil cup, 20 whereby the operative parts may be oiled continually, thereby assuring proper operation of the device and making it impossible for the parts to rust.

A further object is to generally improve 25 and simplify the construction and operation of devices of this character and increase the efficiency thereof without materially increasing the cost of the same.

With the above and other objects in view, 30 my invention consists in certain novel constructions, combinations, and arrangements of parts to be hereinafter more fully described, claimed, and illustrated in the accompanying drawings, in which,

35 Figure 1 is a vertical longitudinal section, partly in elevation of my device in use; and Fig. 2 is a side elevational view.

Referring more specifically to the drawings in which similar reference characters designate corresponding parts throughout the 40 several views, 1 designates the screw-eye, the threaded end of which may be readily secured in a ceiling or the like, as shown at 2, while the lower end 3 is mounted upon the bolt 4 within the oil cup 5. It will be understood that the bolt 4 is positioned transversely through the oil cup 5 which is preferably in the form of a bell or the like and has its lower end 6 formed into opposite directed upwardly curved hooks 7. The bolt 4 is secured in position by a nut 8 and is prevented from turning by the lug 9 in one side of the cup 5 and projecting into the opening in which the head of the bolt 4 is engaged, said head having a notch 10 to receive the lug 9.

It will be understood that the upper end of the cup 5 is flared and that a suitable quantity of oil or the like is placed in said cup, as shown at 11. I also prefer to have 50 the opposite sides of the cup flattened, as clearly shown in Fig. 2. This, however, is not absolutely essential and the cup may be of any desired form. It will further be understood that many minor changes in the details of construction and arrangements of parts may be made within the scope of the appended claims without departing from the spirit of my invention or sacrificing any of the advantages of the same. 65

It will be particularly noted that I have provided a very simple suspending device or hanger which is especially adapted for porch swings and which will preclude all liability of noise and facilitate the easy or smooth 70 operation of the swing, the parts being capable of being easily manufactured and readily assembled and not liable to get out of order. 75

What I claim is:—

1. A device of the class described comprising a suspending member having a perforated lower end, a transversely extending bearing member rotatably mounted intermediate of its ends in the perforated end of the suspending member, a cup carried by said bearing member upon its opposite ends, and a hook formed on the cup. 80

2. A device of the class described comprising a vertically disposed suspending member, a transversely extending bearing member rotatably supported in the lower end of said suspending member, an oil cup supported upon the opposite ends of said bearing member, means formed on said cup for engagement with said bearing member to prevent relative rotation of said bearing member and the cup, and a hook formed on said cup. 90

3. A device of the class described comprising a lubricating cup having alined openings in its opposite sides, a bearing member positioned in said alined openings, said bearing member having a notch formed in one end, a lug carried by said lubricating cup and engaged in said notch to prevent rotation of said bearing member, hooks carried by said lubricating cup, and a suspending member mounted upon said bearing member. 100

4. A device of the class described comprising a suspending member having a perforated lower end, a bearing member extending transversely through the perforated 110

lower end of the threaded member, an oil cup supported upon the opposite ends of said bearing member, means for preventing turning of said bearing member relatively to said cup, and hooks formed on the lower end of said cup.

5. A device of the class described comprising a lubricating cup, having alined openings in its opposite sides, a bearing member 10 extending transversely through said cup and having its opposite ends disposed in the alined openings in said cup, one end of said bearing member having a notch formed therein, a lug formed on one side of said cup 15 and projecting into one of said openings therein to engage the notch in said bearing member, a hook carried by said cup, and a suspending member loosely mounted upon said bearing member within the walls of said 20 cup.

6. A device of the class described comprising

ing a cup having alined openings in its opposite sides, a bolt extending transversely through said cup and having the head thereof disposed in one of said openings, the opposite end of said bolt projecting through the other of said openings, the head of said bolt having a notch formed therein, a lug formed on the wall of said cup and projecting into one of the openings therein to engage the notch in the head of said bolt, means mounted on the projecting portion of said bolt to maintain the same in position with relation to the said cup, a hook carried by said cup, and a suspending member 30 loosely mounted at one end upon said bolt.

In testimony whereof I hereunto affix my signature in the presence of two witnesses.

HARLIN EDGAR STEWART.
